United States Patent Office.

M. K. BUTTERFIELD, OF EDDYVILLE, NEW YORK.

Letters Patent No. 99,288, dated February 1, 1870.

IMPROVEMENT IN FENCE-POSTS.

The Schedule referred to in these Letters Patent and making part of the same.

To all whom it may concern:

Be it known that I, M. K. BUTTERFIELD, of Eddyville, in the county of Cattaraugus, and State of New York, have invented a new and valuable Improvement in Fence-Post; and I do hereby declare that the following is a full, clear, and exact description of the construction and operation of the same, reference being had to the annexed drawings, making a part of this specification, and to the letters and figures of reference marked thereon.

Figure 1 is a view of the fence-post as it appears in front.

Figure 2 is a side view of the same.

My invention relates to fence-posts; and

It consists in improvements upon my patent of September 21, 1869, intended to render my said patented post more generally useful in the construction of fences and gates.

My post is constructed of cast-iron, as described in my said Letters Patent, but instead of the openings therein, and hooks for attaching the fence-rails, I cast flanges or shelves thereon, as shown by *a* of the drawings.

I also make the top of the post sharp and pointed, as shown at *c*.

These devices enable the operator to attach the fence-rails to the posts, by making grooves in the ends of said rails, that will clasp the thin sides of the posts in the form of jaws, and find support upon the shelves *a*. The upper rails may be cut out and lapped over, as shown on fig. 1, the end of each being pierced and held in place by the pointed top of the post, as represented on said figure.

This method of attachment is peculiarly well adapted to picket fences, but other styles of fences may be constructed in the same manner. When desirable, the rails may be passed to their supports from the top of the posts.

What I claim as my invention, and desire to secure by Letters Patent, is—

The flange *a* and point *c*, as an improvement upon my fence-post patented September 21, 1869.

In testimony that I claim the above, I have hereunto subscribed my name, in the presence of two witnesses.

M. K. BUTTERFIELD.
